UNITED STATES PATENT OFFICE

2,446,660

VARIABLE-SPEED DRIVE FOR ELEVATORS

Stanley A. Mulkey and Grant E. Hatcher, Lee's Summit, Mo., assignors to Sam Mulkey Company, Kansas City, Mo., a partnership

Application May 27, 1946, Serial No. 672,662

4 Claims. (Cl. 198—203)

1

This invention relates to a variable speed drive, and more particularly to a variable speed drive for elevators of the endless conveyor type.

Elevators of the endless conveyor type usually consist of a boom which may be elevated to various inclinations for delivering material to any suitable delivery point. Such conveyors are usually driven from the lower end whereby the force is exerted to the return portion of the conveyor, causing the drive to operate at a disadvantage and requiring that the conveyor be relatively tight; otherwise, the looseness thereof at the lower end will provide slack that will permit vibration and excessive wear on the conveyor parts. Such equipment is usually left in the field at great distances from the farmer's house where it is easy for someone to remove the drive mechanism and steal same. It is inviting loss to leave such equipment in the field; however, the drive equipment is the portion of such an elevator that is most easily disposed of and with conventional equipment the drive is usually left on the machines while in the field.

The principal objects of the present invention are to provide a variable speed drive for conveyor type elevators which may be easily attached or detached from the conveyor; to provide a drive mechanism which may be attached to the upper end of the elevator for driving the conveyor; to provide a drive mechanism capable of two speeds to adapt the elevator for handling various types of materials; to provide a drive mechanism with a tubular shaft adapted to engage over a driven shaft to align and support the drive mechanism on the device to be driven; and to provide a variable speed drive mechanism which is simple to apply to the elevator, yet is sturdy, compact and requires substantially no alignment to apply same.

In accomplishing these and other objects of the present invention, we have provided improved details of structure, the preferred forms of which are illustrated in the accompanying drawings wherein:

Fig. 1 is a side elevational view of a conveyor type elevator equipped with a variable speed drive embodying the features of the present invention.

Fig. 2 is a perspective view of the variable speed drive.

Fig. 3 is a plan view of the variable speed drive, portions of the gear reduction housing being broken away to better illustrate the relation of the gears therein.

Referring more in detail to the drawings:

1 designates a conveyor type elevator consisting of 55 end 43 thereof provides a suitable support for a

2

of a boom 2 having a suitable support 3 at the lower end thereof, said boom preferably being provided with struts 4 pivotally connected to the boom as at 5, said struts having wheels 6 on the lower ends thereof. A line 7 is connected to the lower ends of the struts and adapted to be wound on a suitable winch mechanism indicated at 8 to draw the lower end of the strut towards the lower end of the boom to raise the upper end thereof to any suitable elevation. Operating on the boom is a conveyor 9 preferably of the endless type such as chains 10 connected by means of flights 11, the upper ends of said chains operating over sprockets 12 mounted on shafts 13 supported in bearings 14, the ends 15 of the shaft 13 extending outwardly from the boom a substantial distance for a purpose later described.

The lower end of the conveyor preferably operates over sprockets mounted on a shaft 16 which also extends outwardly from the sides of the boom. The outwardly extending portions of the shafts 13 and 16 are adapted to support and drivingly connect variable speed driving mechanism now to be described.

25 The variable speed drive consists of a housing 18 having a side wall 19 and a cover plate 20 closing the open side 21 of said housing opposite the side 19. The cover plate 20 and side wall 19 are preferably provided with bearing bosses 22 and 30 respectively adapted to receive a shaft 24 having bores 25 in the ends thereof. The shaft 24 may be entirely tubular if desired, said bores in the shaft 24 being of such size as to receive the ends 15 of the shaft 13, aligning apertures 26 and 35 being provided in the shafts 24 and 13 to receive a pin 28 to secure said shafts together and provide driving connection therethrough. Mounted on the shaft 24 in the housing 18 is a gear 29 meshing with a pinion 30 fixed to a shaft 31 rotatably supported in spaced relation to the shaft 24 in bearing bosses 32 and 33 on the plate 20 and side wall 19 respectively. The gear 29 and pinion 30 are preferably located adjacent the side wall 19. Adjacent the plate 20 and mounted on the shaft 31 is a gear 34 meshing with a pinion 35 mounted on a shaft 36 rotatably supported in bearing bosses 37 and 38 in the plate 20 and side wall 19 respectively. Both of the shafts 31 and 36 have ends 39 and 40 projecting outwardly relatively to the bearings adapted to receive a sheave pulley 41 thereon.

The gear reduction unit is preferably suitably mounted on one end of the structural frame 42, said frame being of such length that the other

prime mover 44. The prime mover 44 is preferably secured to the structural frame by means of bolts 45 extending through slots 46 in the upper face of said structural frame whereby the prime mover may be moved toward or away from the gear reduction housing 18. The prime mover preferably is provided with a sheave pulley 47, a belt 48 operatively connecting the sheave pulleys 41 and 47.

In the illustrated instance the prime mover is so mounted on the frame that the driving connection is made with the shaft 36 and it can be seen by Fig. 3, a substantial reduction or double reduction may be obtained through the reduction gearing providing a suitable drive for heavy loads on the conveyor. In cases of light loads, permitting faster operation, the bolts 45 may be loosened and the prime mover moved towards the gear reduction unit 18. The sheave pulley 41 may then be removed from the end of the shaft 36 and applied to the end of the shaft 31. The belt is then placed on the sheave and the prime mover moved away from the gear reduction unit until the belt is tight and then the bolts 45 may be tightened to hold the same in place. When the drive is to the shaft 31, it may be readily seen that there is only a slight reduction in the drive to the conveyor.

In this structure the shaft 24 being sleeved over the end of the shaft 13, the entire weight of the drive unit may be carried thereon and pivoted around said shaft 13. In order to support the other end of the drive unit and preferably to maintain said unit level, particularly in case of the use of gasoline engines for the prime mover, a link 49 is connected to the prime mover end of the frame 43, the other end of said link being connected to the boom as at 50, a slot 51 being provided in the link whereby the vertical adjustment may be had with the prime mover end of the structural frame and gear reduction unit. The only connection between the variable speed drive and the conveyor type elevator and boom is the bolt fastening the link to the elevator as at 50 and the pin 28 which secures the shaft 24 to the shaft 13; therefore, by the removal of these two fastening devices the entire drive unit may be removed from the conveyor and when the elevator is not in use the drive unit may be kept in the barn or other suitable safe place.

When it is desired to use an elevator of this type, the variable speed drive unit is taken from its place of protection into the field wherever the conveyor might be located. The shaft 24 is then sleeved over the projecting end of either the shaft 13 or 16 depending upon the end from which it is desired to drive the elevator and as will be noted, both ends of the shaft 24 project from the side of the housing whereby the drive unit may be applied to either side of the elevator depending upon the particular requirement thereof. After sleeving the shaft 24 over the shaft 13, the apertures 26 and 27 are aligned and the pin 28 applied thereto. This operation may be performed with the prime mover end of the unit hanging free. After securing the shafts 13 and 24 together, the prime mover end of the driving unit is preferably lifted to approximately a horizontal position and a bolt applied to the slots 51 as at 50 to connect the unit to the boom of the elevator. The elevator is then inclined to a suitable height to provide a proper delivery to the point desired.

It is believed obvious that we have provided an elevator and variable speed drive therefor which provides great flexibility in the attachment of the

drive to the elevator, gives a variation in speed, and is easily removed and applied to the elevator whereby said drive unit may be moved to a safe place when not in use.

What we claim and desire to secure by Letters Patent is:

1. In an elevator, an endless conveyor, a conveyor shaft on the elevator, means on the conveyor shaft engaging the conveyor for driving same, said shaft extending outwardly from said elevator, a driving mechanism, a driving shaft in the driving mechanism, said driving shaft having a bore removably sleeved over a portion of the conveyor shaft and having driving connection therewith for supporting the driving mechanism for pivotal movement about the axis of said conveyor shaft, and means pivotally mounted on the driving mechanism and spaced radially of said driving shaft adapted for adjustably connecting the driving mechanism with the elevator for holding said mechanism in adjusted position.

2. In an elevator, a boom having upper and lower ends, an endless conveyor operating over the boom, a conveyor shaft at the upper end of the boom, means on the conveyor shaft engaging the conveyor for driving same, said shaft extending outwardly from said boom, a gear reduction unit, a drive shaft in the gear reduction unit, said driving shaft having a bore adapted to sleeve over a portion of said conveyor shaft and having driving connection therewith for supporting the gear reduction unit for pivotal movement about the axis of said shaft, means for driving the gear reduction unit, and means spaced from the drive shaft adjustably connecting the gear reduction unit with the boom for securing the gear reduction unit in adjusted position.

3. In an elevator, a boom having upper and lower ends, an endless conveyor operating over the boom, a conveyor shaft rotatably mounted at the upper end of the boom, means on the conveyor shaft engaging the conveyor for driving same, said shaft extending outwardly from said boom, a gear reduction unit, a drive shaft in the gear reduction unit, said driving shaft having a bore adapted to sleeve over a portion of said conveyor shaft and having driving connection therewith for supporting the gear reduction unit for pivotal movement about the axis of said shaft, a prime mover having operating connection with the gear reduction unit for driving the shaft therein, a frame having connection with the gear reduction unit and extending therefrom for supporting the prime mover, and means spaced from the drive shaft for adjustably connecting the frame with the boom for securing the prime mover and gear reduction unit in adjusted position.

4. In an elevator, a boom having upper and lower ends, an endless chain conveyor operating over the boom, a conveyor shaft at the upper end of the boom, sprockets on said shaft and engaging the conveyor for driving same, said shaft extending outwardly from said boom, a gear reduction unit, a drive shaft rotatably mounted in the gear reduction unit and having an end projecting therefrom, said driving shaft having a bore in the projecting end adapted to sleeve over a portion of the outward extension of said conveyor shaft for supporting the gear reduction unit for pivotal movement about the axis of said shaft, means keying the conveyor shaft to the portion of the drive shaft sleeve thereon, a plurality of driven shafts in the gear reduction unit, a prime mover having selective operating connec-

tion with the driven shafts in the gear reduction unit for varying the speed reduction therein, a frame having connection with the gear reduction unit and extending therefrom for supporting the prime mover, and means pivotally mounted on the frame remotely of the gear reduction unit for adjustably connecting the frame with the boom for securing the prime mover and gear reduction unit in adjusted position.
